Fig. 1

Fig. 2

To all whom it may concern:

Be it known that I, Ralph P. Sant, a citizen of the United States and resident of South Milwaukee, in the county of Milwaukee and State of Wisconsin, have invented a new, original, and ornamental Design for Insulator Rack, of which the following is a specification, reference being had to the accompanying drawing, forming a part hereof.

Fig. 1 is a perspective view of an insulator rack showing my new design; and

Fig. 2 is a side-elevational view thereof.

The broken line showing of an insulator and supporting rod in Fig. 2 is for illustrative purposes only.

I claim:

The ornamental design for an insulator rack, as shown and described.
